UNITED STATES PATENT OFFICE

ALBERT RIETH, OF PROVIDENCE, RHODE ISLAND

MASSAGING DEVICE

Application filed August 1, 1927. Serial No. 209,827.

My invention relates to massaging devices, particularly to a massaging device having a plurality of massaging rollers thereon. The main object of my invention is to provide a device of this description containing a plurality of rollers having handles therefor at each end thereof expandable to permit insertion of a human member within said rollers and compressible by manual pressure or otherwise to grip said human member while said rollers are revolved thereon. My device thus permits an intensive gripping action on each side of the human member being massaged, as well as the usual rubbing action of the roller.

20 A further object of my invention is to provide, I believe, for the first time a massaging roller flexible substantially throughout the length thereof, so that it may flex to be adjacent to the human member being massaged substantially throughout the length thereof, thereby insuring maximum contact of the roller with the surface being massaged.

A further object of my invention is to provide novel means for mounting massaging rollers in devices of this description.

Further objects of the invention are to provide a massaging device simple in construction and efficient in its action.

30 These and such other objects of my invention as may hereinafter appear will be best understood from a description of the accompanying drawings which illustrate embodiments thereof.

33. In the drawings Fig. 1 is a plan view of a massaging device constructed in accordance with the principles of my invention closed in unused position.

Fig. 2 is a plan view thereof with the rollers 40 and gripping means therefor expanded around a human member, showing how in use the device may be manually compressed to exert a radial pressing action as well as a rubbing action on the member being massaged. 45

Fig. 3 is a fragmentary side elevation partially shown in section of an individual roller with its preferred type of mounting means.

Fig. 4 is an end view taken along the line 4-4 of Fig. 3.

Fig. 5 is a fragmentary view of a modified form of my invention wherein each handle section thereof carries a plurality of rollers.

In the drawings, wherein like characters of reference indicate like parts throughout, 10 generally indicates my improved massaging device. 12 indicates suitable massaging rollers. While any type of massaging roller may be employed, having the usual massaging protuberances 14 thereon, I preferably employ a massaging roller flexible substantially throughout its length to permit a maximum amount of contact against the periphery of the usual curved surface being massaged. 55 60

As massaging rollers are so well known in the art and as any of the well known types of massaging protuberances may be employed, in the claims I merely refer to these elements 12 as massaging rollers. 65

As shown in Fig. 2, I provide handles or gripping means 16 adapted to compress the rollers radially inwardly on opposite sides of the human member being massaged. While the preferred embodiment of my invention is constructed of a size to normally massage a usual human arm or leg, it is obvious that it may be constructed of a size to fit around the torso or any other human member. The gripping means 16 in my preferred embodiment comprises the handle sections 18 having their outer ends suitably pivoted

18, having their outer ends suitably pivoted together as at 20 and having mounting means 22 for the rollers at their inner ends. While any suitable type of an axle or other mounting means may be employed for mounting said rollers on the handles thereof, I preferably employ the novel mounting means about to be described. As more clearly shown in Fig. 3, I preferably construct said massaging rollers 12 hollow and I insert in each hollow end thereof a ball bearing race 24, which may, if desired, be suitably clamped or otherwise attached within the hollow end 26 thereof and I mount within said ball bearing race the inner end 28 of a trunnion 30 adapted to have the outer end 32 thereof project through a suitable mounting hole 34 in the inner end of the handle 18 and be fixedly secured thereto by the nut 36. As shown in Fig. 3, the ball bearing race 24 with attached trun-

nion 30 may be readily removed from within its bearing 38 by unscrewing the screws 40 and removing the end bearing cover plate 42 therefrom.

5 In Fig. 5 I have shown a modified form of my invention employing a plurality of massaging rollers 12 on each handle section 18.

10 The operation of my invention is diagrammatically illustrated in Fig. 2. The handle sections 18 may be readily pivoted to an open position and as the flexible rollers are moved radially outwards, it is obvious that they will circumferentially bend. The massaging device is then placed around the 15 human member 50 desired to be massaged and the handle sections 18 compressed together by means of the hands 52 functioning on the handles on opposite ends of my device. The device may then be rolled as usual 20 over the surface of the member desired to be massaged and it is apparent that I have secured a radially compressing action, as well as the usual rubbing action, thereby greatly stimulating the circulation of the blood and 25 having other beneficial effects upon the person being massaged. As stated, as the improved type of roller, which I preferably employ, is flexible substantially throughout its length, it readily bends as shown in Fig. 2 30 to provide optimum amount of contact with the surface being massaged.

It is understood that my invention is not limited to the specific embodiment shown and that various deviations may be made therefrom without departing from the spirit and scope of the appended claims.

35 What I claim is:

1. A massaging device comprising cylindrical flexible massaging means and handles 40 for each end thereof, each comprising two members hinged together at their outer ends and having mounting means for the ends of the massaging means at their inner ends.

2. A massaging device comprising a plurality of flexible massaging rollers and handles for each end thereof, each comprising two members hinged together at their outer ends and having mounting means for the ends of the rollers at their inner ends.

50 3. A massaging device comprising two flexible massaging rollers, trunnions therefor at each end thereof and handles for each end thereof each comprising two members hinged together at their outer ends and having mounting means for said trunnions at their inner ends.

4. In a massaging device, a rubber hollow roller of flexible material, having massaging protuberances on the outer periphery thereof, a ball bearing race mounted within each hollow end thereof and a trunnion projecting outwardly from each ball bearing race adapted to be fixedly secured to a handle to permit revolution of said roller on said races.

65 5. In a massaging device for human mem-

bers, a massaging rubber roller of general cylindrical shape flexible substantially throughout the length thereof and having massaging protuberances on the outer periphery thereof and of a length capable of partially encompassing said human member and handle means attached to each end thereof for applying the same to said human member.

70 In testimony whereof I affix my signature.

ALBERT RIETH.
